UNITED STATES PATENT OFFICE.

LADBROOK H. FREEMAN, OF CLEVELAND, OHIO, ASSIGNOR TO THE GUGGENHEIM LAUNDRY MACHINERY COMPANY, OF CLEVELAND, OHIO, A CORPORATION OF OHIO.

BOSOM-BOARD.

1,144,118.

Specification of Letters Patent. Patented June 22, 1915.

Application filed September 29, 1913. Serial No. 792,382.

To all whom it may concern:

Be it known that I, LADBROOK H. FREEMAN, a citizen of the United States, residing at Cleveland, in the county of Cuyahoga and 5 State of Ohio, have invented certain new and useful Improvements in Bosom-Boards, of which the following is a specification.

This invention relates generally to bosom boards and particularly to stretching devices for use on such boards.

More specifically the invention relates to a stretcher for stretching the forward skirt portion of a shirt over a bosom board.

The invention may be further briefly summarized as consisting in the construction and combination of parts hereinafter set forth in the following description, drawings and claims.

Referring to the drawings, Figure 1 is a 20 side elevation of a portion of an ironing press provided with my improved stretcher; Fig. 2 is a front elevation of the device; Fig. 3 is a plan view; Fig. 4 is an end elevation with the jaws open; and Fig. 5 is a similar 25 view with the jaws closed.

In carrying out the invention any preferred form and construction of parts may be employed so long as they possess the necessary characteristics, but I have shown 30 one arrangement in the drawings which is effective in operation, and in such embodiment 1 represents the main frame of the machine which is provided with a suitable ironing board support 2 upon which is 35 mounted an ironing board 3 of any desired form. This ironing board 3 in this instance is provided with a yoke ironing member 4, a yoke ironer 5, and upon its upper surface near the yoke ironer with a neck band 40 former 6. Coöperating with the ironing board and neck band former is an ironing chest 7, which is supported on suitable arms 8 mounted on brackets 9 secured to the main frame. The ironing 45 chest 7 is operated through the link 10, operating arms 11, and links 12 connected on either side of a driving gear 13. This mechanism is not fully or completely shown for the reason that it forms no part of the 50 invention but merely illustrates one type of machine to which the device may be applied. Mechanism is also provided for stretching the bosom over the ironing board, and it comprises a bracket 14 secured to the 55 front face of the ironing board support 2

as shown in Fig. 1. This bracket 14 has outwardly extending bearing portions 15 and 16, the portion 16 being long enough to extend to a point at one side of the ironing board and there provided with a friction 60 disk 17, for a purpose to be described. The inner face of the bearing 15 is provided with a pin 18 for a purpose to be described. Rotatably mounted in these bearings 15 and 16 is a shaft 19 having keyed to it between the 65 two bearings a mutilated gear 20 which meshes with another mutilated gear 21 mounted upon a shaft 22 pivoted in a bearing 23 forming a part of a stretcher bracket 24 provided with a bifurcated bearing portion 25 loosely mounted upon the shaft 19. The stretching bracket is provided with a recessed stretcher portion 26 arranged transversely with respect to the ironing board and extending across the front, as shown in Fig. 70 75 1. Coöperating with this member is a clamping roller 27 covered with rubber and mounted in a frame 28 which extends about the bracket 24 and to the rear thereof and is swiveled by means of a suitable bearing 80 85 29 upon the shaft 19. This frame 28 is provided with a cam portion 30 adapted to co-operate with a cam 31 secured on the end of the shaft 22. A spring 32 is arranged between the bracket 24 and the stationary 90 95 bracket 14 and normally tends to draw the bracket 24 inward toward the end of the ironing board and this inward movement is limited by a shoulder 33 forming a part of the bracket and engaging the pin 18. The shaft 19 is manipulated by a suitable lever 34 keyed to the shaft and having a boss 35 provided with a threaded opening in radial alignment with the periphery of the disk 17. Threaded in the opening of the boss 35 is 100 105 a rod 36 provided with a hand grip 37 at its upper and with a shoe 38 at its lower end for engagement upon the periphery of the friction disk 17. The arrangement of this mechanism is such that when the shirt is being placed upon the machine the forward skirt portion is drawn down over the transverse member 26, when the parts are in the position shown in Fig. 4. The operator then rotates the rod 36 to release the shoe 38 from engagement with the friction disk and pulls forward upon this rod with the result that the lever 34 is rocked in a counter clockwise direction, causing the shaft 19 to be rotated, and likewise the gear 20. The rota- 110

tion of the gear 20, however, rotates the gear 21 in a clockwise direction, causing the cam 31 to engage the cam portion 30 of the frame 28, causing the roller 27 to be brought up 5 snugly against the transverse stretching member 26 of the bracket 24. When this clamping operation has taken place, the further forward movement of the rod 36 of the lever 34 causes the frame 28 as well as the 10 bracket 24 to be moved forward or to be rocked in a counter clockwise direction, with the result that the bosom is stretched over the ironing board. Upon the rotation of the rod 36 by means of the hand grip 37, the 15 parts are locked in this position by the engagement of the friction shoe 38 with the periphery of the friction disk. To release the device the operator rotates the rod 36 to withdraw the shoe 38 and the parts are 20 returned to normal position, the clamp being opened by the extreme forward movement of these parts.

Having described my invention, I claim:

25 1. In a bosom board structure, a bosom board, means for holding the shirt at the neck, and a bosom stretcher comprising a clamp, a single element for opening and closing the clamp and for moving it in the 30 stretching and releasing operation.

2. In a bosom board structure, a bosom board, means for holding the shirt at the neck, and a bosom stretcher comprising a clamp mounted to move bodily, a single operating element, connections between said element and the clamp to cause it to move into clamping position, connections between said operating element and the clamp for moving it bodily, and means for holding said 40 member in any adjusted position.

3. In a bosom board structure, a bosom board, and a bosom stretcher comprising a supporting bracket suitably mounted, a stretcher bracket pivotally mounted in said 45 supporting bracket, a clamping frame also pivotally mounted, mechanism between the stretcher bracket and the clamping frame for drawing the same together and for finally moving both of said members in 50 clamped position to stretch the bosom over the ironing board.

4. In a bosom board structure, a bosom board, and a bosom stretcher comprising a supporting bracket, a stretcher bracket pivotally mounted in said supporting bracket, a clamping frame also pivotally mounted, an operating device, and suitable mechanism between said operating device, said stretcher and said clamping frame for causing a 60 movement of the operating device to close the clamping frame upon the stretcher bracket and a further movement to move said parts while in a clamped position to draw the bosom over the ironing board.

65 5. In a bosom board structure, a bosom

board, and a bosom stretcher comprising a supporting bracket, a stretcher bracket pivotally mounted in said supporting bracket, a clamping frame also pivotally mounted, an operating device, suitable mechanism between said operating device, said stretcher and said clamping frame for causing a movement of the operating device to close the clamping frame upon the stretcher bracket and a further movement to move 70 said parts while in a clamped position to draw the bosom over the ironing board, and means for holding the operating device in any adjusted position.

6. In a bosom board structure, a bosom board, and a bosom stretcher comprising a supporting bracket, a stretcher bracket pivotally mounted in said supporting bracket, a clamping frame also pivotally mounted, an operating device, and suitable gearing between said operating device, said stretcher and said clamping frame for causing a movement of the operating device to close the clamping frame upon the stretcher bracket and a further movement to move 75 said parts while in a clamped position to draw the bosom over the ironing board.

7. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 80 said parts while in a clamped position to draw the bosom over the ironing board.

85 8. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 90 said parts while in a clamped position to draw the bosom over the ironing board.

90 9. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 95 said parts while in a clamped position to draw the bosom over the ironing board.

95 10. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 100 said parts while in a clamped position to draw the bosom over the ironing board.

100 11. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 105 said parts while in a clamped position to draw the bosom over the ironing board.

105 12. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 110 said parts while in a clamped position to draw the bosom over the ironing board.

110 13. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 115 said parts while in a clamped position to draw the bosom over the ironing board.

115 14. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 120 said parts while in a clamped position to draw the bosom over the ironing board.

120 15. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 125 said parts while in a clamped position to draw the bosom over the ironing board.

125 16. In a bosom board structure, a bosom board, and a bosom stretcher comprising a supporting bracket, a stretcher bracket pivotally mounted in said supporting bracket, a clamping frame also pivotally mounted, an operating device, suitable gearing between said operating device, said stretcher and said clamping frame for causing a movement of the operating device to close the clamping frame upon the stretcher bracket and a further movement to move 130 said parts while in a clamped position to draw the bosom over the ironing board.

able mechanism between said operating device, said stretcher and said clamping frame for causing a movement of the operating device to close the clamping frame upon the
5 stretcher bracket and a further movement to move said parts while in clamped position to draw the bosom over the ironing board, and means for holding the operating device in any adjusted position, and comprising a
10 disk having an edge face, a clamping shoe slidably mounted on the operating device

and in a position to engage said edge face, and a handle threaded on said operating device and adapted to force said shoe into engagement with the edge face.

15

In testimony whereof I affix my signature in presence of two witnesses.

LADBROOK H. FREEMAN.
